UNITED STATES PATENT OFFICE

123,925

DESIGN FOR AN ELECTRIC SIGN

Kenneth F. Smith, Lima, Ohio, assignor to Neon Products, Inc., Lima, Ohio, a corporation of Ohio

Application September 18, 1939, Serial No. 87,278

Term of patent 3½ years

To all whom it may concern:

Be it known that I, Kenneth F. Smith, a citizen of the United States, residing at Lima, in the county of Allen and State of Ohio, have invented a new, original, and ornamental Design for an Electric Sign, of which the following is a specification, reference being had to the accompanying drawing, forming part thereof.

Figure 1 is a front perspective view of an electric sign, showing my new design.

Figure 2 is a side elevation of the same.

Figure 3 is a rear view of the sign with a portion of the back wall removed to show the location of the incandescent lamp within the housing.

I claim:

The ornamental design for an electric sign, as shown.

KENNETH F. SMITH.
